UNITED STATES PATENT OFFICE.

HENRY C. BOTHWELL, OF McARTHUR, OHIO.

DESIGN FOR A BROOM-RACK.

SPECIFICATION forming part of Design No. 31,823, dated November 14, 1899.

Application filed October 17, 1899. Serial No. 733,929. Term of patent 14 years.

To all whom it may concern:

Be it known that I, HENRY C. BOTHWELL, of McArthur, in the county of Vinton and State of Ohio, have invented and produced a new and original Design for a Broom-Rack, of which the following is a full, clear, and exact description.

Reference is to be had to the accompanying drawing, forming a part of this specification, in which the figure is a perspective view of a broom-rack, showing my design.

The design in its entirety consists of a base A, from the ends of which rise standards B, ornamented at their upper ends by cross-bars C, connected with each other by spaced longitudinal bars D, each appearing with a row of apertures E, the outer faces of said standards carrying brackets F near their upper ends and keepers G near the base A, the bracket-shelves having apertures and the

keepers top recesses, the base A appearing on top, with a receptacle H extending between the standards and having a V-shaped bottom I, with a central longitudinal partition J, from which extend transverse partitions K to divide each side of the receptacle H into a plurality of compartments open at the top. 25

The leading feature of my design consists of the compartment-receptacle, the standards, the cross-bars, and the apertured longitudinal bars. 30

Having thus described my invention, I claim as new and desire to secure by Letters Patent—

The design for a broom-rack herein shown and described. 35

HENRY C. BOTHWELL.
